CLAIM

The ornamental design for a combined Christmas tree ornament hanger and cap, as shown and described.

DESCRIPTION

FIG. 1 is a front elevational view of a combined Christmas ornament hanger and cap showing my new design, the rear being identical;

FIG. 2 is a front elevational view of the Christmas ornament hanger, shown separately for clarity of illustration, the rear being identical;

FIG. 3 is a right side elevational view of FIG. 3, the left side being identical;

FIG. 4 is a side elevational view of a cap, shown separately for clarity of illustration, all sides being identical; and,

FIG. 5 is a top plan view of FIG. 4, the surface pattern removed for ease of illustration.

FIG. 1

FIG. 2

FIG. 3

FIG. 4

FIG. 5
